AUDIBLE ROAD SIGNAL

Edward J. Morin, Omaha, Nebr.

Application December 2, 1935, Serial No. 52,550

2 Claims. (Cl. 116—67)

This invention relates to signals and more particularly to an audible road signal particularly adapted for use in connection with roadway, highway and railway crossings.

5 It is an object of the invention to provide an audible signal which is certain of operation and of few and simple parts requiring no particular attention, adjustment or repair during use which can be installed and operate with certainty in 10 comparatively remote and isolated situations for warning vehicular traffic of the proximity and approach thereof to a said crossing or intersection.

With the foregoing and other objects in view, 15 the invention will be more fully described hereinafter and more particularly pointed out in the claims appended hereto.

In the drawing wherein like symbols refer to like or corresponding parts throughout the several views:

20 Figure 1 is a top plan view of a portion of a warning signal embodying the present invention.

Figure 2 is a transverse section of a cover employed taken on line 2—2 of Figure 1.

25 Figure 3 is a transverse section of the cover taken on line 3—3 of Figure 1.

Figure 4 is a transverse section of the cover and certain adjunct parts employed, the view being taken on line 4—4 of Figure 1.

30 Figure 5 is a longitudinal sectional view of the cover and certain parts shown in Figure 1, taken on line 5—5 of said figure.

Figure 6 is a diagrammatic top plan view of 35 a railway and highway crossing or intersection of a roadway and road and illustrating the present invention combined therewith.

Referring now to the drawing for a more particular description, 10 indicates an elongated box adapted to be embedded transversely of a roadway or at an inclination with respect thereto and below the surface thereof. The box may be formed of any suitable material such as cast iron, concrete or the like and is provided with oppositely disposed side walls 11 and may have an open or closed bottom and end walls as may be desired. For comparatively wide roads three or more of the boxes may be employed of assorted lengths in order to span and fit such road such boxes or supports being disposed end to end.

50 The box is provided with a cover or member 12 formed of cast iron having step-cut side edges 13 which are adapted to abut the upper edges of the side walls 11 and to be removably secured thereto by means of screws 14 or any suitable

keepers. For certain types of installations the said box or boxes may be dispensed with.

The cover has a plurality of apertures 15 extending in alignment with respect to each other longitudinally of the cover. Transversely disposed webs 16 are formed integral with the cover providing the spaced apart apertures 15.

A plurality of gongs are loosely supported within the box 10 preferably upon studs 17 secured to the cover at the underneath side thereof. The 10 gongs 18 are provided with apertures 19 of larger diameter than the studs 17 whereby the gongs are free to have vertical movements on said studs and to also create a penetrating and comparatively loud tone when struck. The gongs are 15 disposed in alignment with respect to each other and usually entirely at one side of the said apertures for purposes later explained.

A shaft 20 is preferably positioned longitudinally of the box extending across each of the 20 apertures and as best shown in Figure 3 is secured to the web by means of cleats 21, the latter being removably secured to the webs 16 by means of suitable keepers such as the screws 22 and it will be understood that as thus described 25 the shaft 20 is free to have journalled movements in the bearings thus provided, said bearings affording a very loose fit preferably.

Clappers 23 are provided for the gongs and, as best shown in Figure 4, the clappers are pivotally mounted for swinging movements on said shaft, said mounting preferably providing a loose fit between the shaft and clapper whereby the clapper is adapted to swing transversely of the shaft in either direction.

35 Each clapper is provided with an arm 24 which normally projects above the outer surface of the cover. The arms 24 are preferably formed integral with the clappers but may consist, if desired, of a yieldable substance such as rubber secured to the clappers by any suitable means. The upper ends of the arms are preferably arcuate in cross section as indicated at 25 when formed of metal. The clappers are of greater weight than the arms for returning the latter to a normal vertical position as shown in Figures 1 and 4 after a swinging movement. At times when an arm swings it may become positioned within the plane of the cover, recesses 26 being provided for said purpose at each side of the apertures 15.

40 Particularly referring to Figure 6, 27 indicates a railroad track and 28 a highway crossing thereof. One each of the said boxes 10 together with the foregoing described parts are positioned at 45 each side of the roadway 27 and embedded in the 50

road 28 and preferably a distance or proximity of two hundred feet from the roadway 27 or a greater or lesser distance in accordance with local conditions and as may be required for a particular installation and situation.

5 It will be understood that the distance between an arm 24 and its next adjacent mate is comparatively minute and preferably not greater than the width of a buggy wheel for insuring that 10 the wheel of said type of vehicle will strike at least one of said arms 24 while traveling over the road toward the roadway crossing or intersection.

15 In operation a vehicle approaching the crossing in the direction of the arrow 29 will actuate at least one arm 24 for ringing a gong and audibly informing the driver of the vehicle that he is approaching a dangerous crossing, said actuation being resultant from the tire or wheel of the 20 vehicle striking said arm and swinging a clapper against a gong.

25 Referring to Figure 6, A indicates a box 10 or installation and warning mechanism which is like the box B and mechanism at the other side of the roadway crossing except that the gongs in the box A are all disposed on that side of the box A opposite to the direction of travel as indicated by the arrow 29; whereas it will be understood that the gongs in the box indicated at B are on the opposite side of the said box with respect to 30 the gongs in the box A, said gongs in both boxes are disposed further from the roadway 27 than are the clappers for said gongs. It will be understood that the boxes are alike in construction and that the said positioning of said gongs may 35 be consummated by turning one of the boxes end for end during an installation thereof whereby in operation the vehicle approaching the crossing and traveling in the direction of the arrow 29 will ring the gongs or a gong in the box A and when 40 said vehicle has crossed the roadway 27 and during a continuation of travel in the direction of the arrow 29 and while traveling over the box B no gongs will sound loudly from the latter since, while the clapper of the box B will be caused to 45 swing, yet said clapper does not strike against a gong, the latter being positioned on that side of a clapper from which the vehicle approaches the box B.

50 Conversely, a vehicle approaching the roadway 27 in a direction reverse to the arrow 29 will sound the warning gongs in the box B, to the exclusion of the gongs in the box A. By the said

means a driver of a traveling vehicle will be warned that he is approaching the railway and that said railway or intersection is still ahead of him at the time he receives said warning.

5 The rear of the vehicle will cause a repetition of the warning signal and if desired the invention may be installed inclinedly across a roadway whereby one front wheel of a vehicle actuates the mechanism, the second front wheel to strike an arm causes a succeeding warning sound to be 10 generated, the rear wheels causing two more successive signals.

15 It is obvious that various changes and modifications may be made in the details of construction and design of the above specifically described 20 embodiment of this invention without departing from the spirit thereof, such changes and modifications being restricted only by the scope of the invention as herein claimed.

25 What is claimed is:—

1. An audible signal for road crossings comprising an elongated box adapted to be embedded transversely of a roadway below the surface thereof, a cover for the box having a plurality of 30 apertures, a plurality of gongs loosely supported within said box at one side of said apertures, a shaft extending longitudinally of the box and across said apertures, swingable clappers for the gongs pivotally mounted on said shaft, said clappers each having an arm normally projecting 35 above the outer surface of said cover, said clappers being of greater weight than said arms for returning said arms to a normal vertical position.

2. In combination, a road disposed at an intersecting angle with respect to a roadway, 40 audible signals disposed at opposite sides of said roadway, each signal comprising an elongated member having a plurality of apertures disposed across said road in substantial horizontal alignment with the surface thereof, a plurality of 45 gongs under each said member, a plurality of clappers for the gongs under each said member, said clappers adapted to be swung for striking and sounding the gongs, and arms associated with the clappers and extending through said apertures, said clappers being of greater weight than 50 said arms for returning the latter to a normal vertical position, the gongs of each said signal being disposed further from said roadway than the clappers thereof.

55 EDWARD J. MORIN.
